UNITED STATES PATENT OFFICE

ADAM CLARK, OF WILLOWS, SASKATCHEWAN, CANADA

EARTH-EXCAVATING MACHINE

Application filed December 1, 1928. Serial No. 323,011.

The invention relates to improvements in earth excavating machines and an object of the invention is to provide a machine wherein a plough is utilized to deliver ploughed dirt into an accompanying relatively large rotating wheel, the wheel having internal buckets which receive and elevate the earth to a point where it is discharged into a receiving trough or chute discharging from the wheel.

10 A further object is to arrange the plough so that the depth of cut can be readily gauged by the attendant and such that the earth dug by the plough will be positively delivered into the interior of the wheel at the lower side thereof.

15 A further object is to provide means interior of the wheel and adapted to deflect any earth dropping from the rising buckets onto the underlying buckets and by so doing prevent the accumulation of dirt around the hub.

20 A further object of the invention is to provide a box for receiving and collecting the earth discharged from the wheel and to provide the box with means whereby it can be readily dumped from time to time as occasion requires.

25 A still further object is to provide a positive means for expelling the dirt elevated by the wheel into the box.

30 With the above more important objects in view, the invention consists essentially in the arrangement and construction of parts hereinafter more particularly described, reference being had to the accompanying drawings, in which:—

Fig. 1 is a side view of the machine.

Fig. 2 is a front end view thereof.

Fig. 3 is a vertical sectional view at 3—3' Figure 1.

40 Fig. 4 is a vertical sectional view at 4—4' Figure 3.

Fig. 5 is a plan view of the plough.

Fig. 6 is a sectional view similar to Figure 4 showing a modified construction.

45 In the drawings like characters of reference indicate corresponding parts in the several figures.

The machine as herein disclosed can be used with or without a collecting box for the excavated earth as the use of the box would

depend on the nature of the work being done by the machine. If the machine is to be used for excavating purposes such as cellars or basements where the earth excavated cannot be directly deposited to the side of the machine, the collecting box will be utilized to hold the excavated earth and the machine will be driven to the point where it is to be dumped from time to time.

Where the machine is to be used for excavating purposes such as trenches or ditches where the earth can be thrown to the side of the ditch, it is not necessary to use the box and accordingly the same can be dispensed with. In the drawings, the machine is shown as embodying the earth receiving box and the details thereof are accordingly herein described.

The main frame of the machine is substantially rectangular and embodies a pair of parallel side beams 1 and 2, a further single side beam 3 spaced from beam 2, a front forwardly extending platform 4 connecting the beams and a rear cross beam 5. An elevated frame 6 is also provided, this being closed at the inner side by the beam 3 and embodying also an outer beam 7 parallel to the beam 3, a forward elevated platform 8 connecting the beam 7 to the beam 3 and a rearward cross beam 9.

A horizontally disposed brace bar 10 is fastened to the elevated platform 8 and crosses the platform 4 and has the end thereof down turned and fastened at 11 to the rear outer corner of the latter platform. An angle iron 12 is secured to the under side of the platform 4 at the rear edge thereof and is extended to provide an angularly disposed brace bar 13 which has the outer end fastened to the under side of the elevated platform 8. An angle iron 14 underlies the beam 5 and has one end thereof extended to provide an angular brace 15 supporting the rear outer corner of the elevated frame.

The platform 4 has the forward end thereof supported by a pivoted truck 16 of any approved design and the truck carries a hitching ring 17 to which the draft animals or a tractor can be attached.

The elevated frame carries more or less

centrally a pair of aligned bearings 18 and 19 which support rotatably a cross shaft 20. On the shaft between the bearings, I mount rotatably a wheel embodying a hub 21, a circular head plate 22 secured to the outer end of the hub, spokes 23 radiating from and attached to the plate and a comparatively wide rim 24 fastened to the outer ends of the spokes, the rim being provided with relatively deep continuous side flanges 25 and 26. The spokes carry flanges 27 passing transversely of the wheel and terminating at the rim flange 26 and each of the flanges 27 is cut and bent to provide deflecting wings 28 and 29. The wings 28 are concentric to the hub and extend transversely of the wheel and the wings 29 also pass transversely of the wheel and form with the retained portions of the flanges 27 and the rim and flanges of the wheel, buckets for gathering and elevating earth deposited in the wheel in a manner later disclosed. Centrally between the buckets so formed, I have provided further buckets formed by fastening somewhat Z-shaped plates 30 to the rim between the flanges.

The buckets indicated generally by the reference character A are all equi-spaced around the circumference of the wheel and when the wheel is rotated in the direction indicated by the applied arrow Figure 4, the buckets at the lower side of the wheel serve to gather and hold earth deposited in the lower side of the wheel and as the wheel rotates, they carry that earth upwardly until it discharges under the action of gravity over the then inclined wings.

Whilst I have entered into a detailed description of the manner in which the buckets are formed, the structure shown might be materially modified without departing from the spirit of the invention as will readily be appreciated.

The beams 1 and 2 are supported by a ground wheel 31, the shaft 32 of which is rotatably mounted in bearings 33 carried by said latter beams. The beams 2 and 3 support a substantially rectangular earth receiving box 34 which has the bottom thereof normally closed by a pair of hinged gates 35 and 36, these gates being releasably held closed by lines 37 and 38 attached to the ends thereof and secured to a winding shaft 39 rotatably carried by the ends of the box and provided forwardly with a winding crank 40. A ratchet wheel 41 is secured to the shaft and a pivoted dog 42 engages the ratchet wheel, such latter parts operating to hold the gates closed.

Obviously if the box be full of earth and it is desired to dump it, it is only necessary to release the dog 42 from the ratchet wheel which fees the gates and permits the earth to discharge.

A suitably supported counter shaft 43 is located above and parallel to the shaft 32 and

these latter shafts carry chain wheels 44 and 45 connected by a driving chain 46. The inner end of the shaft 43 is connected by a universal joint 47 to a further shaft 48 provided with a worm or auger 49 extending into the wheel and operating within a collecting trough 50 which is suitably supported adjustably as indicated at 51 from the beam 3. The trough is adapted to receive the earth discharged by the wings of the buckets A and the worm obviously discharges the earth caught by the trough into the box. The beam 3 carries a downwardly extending guard plate 52 which prevents dirt from escaping out the inner side of the wheel.

A hood 53 of suitable design is carried by the elevated frame and covers the upper side of the wheel. The inner side of the hood is cut away to admit the trough.

A plough 54 is located at the side of the bucket carrying wheel, the plough being permanently fastened to a plough beam 55 positioned parallel to the beam 3. Similar front and rear horizontally disposed spacing arms 56 and 57 are permanently secured to the plough beam and have their inner ends pivotally fastened to the inner side of the main frame.

Means is provided for controlling the depth of cut of the plough, such embodying a link 58 pivotally secured to the plough beam and to the cranked lower end 59 of a control lever 60, the lever being pivotally secured to the elevated frame and being provided with the customary hand latch 61 and detent 62, the detent operating over a quadrant 63 secured to the elevated beam.

The plough beam carries a rotary coulter 64 in advance of the plough and a furrow wheel 65 to the rear thereof and obviously the depth at which the plough cuts can be controlled by the adjustment of the lever 60. The forward end of the plough beam is supplied with a draft ring 66 which is also suitably hitched to a tractor or draft animals.

The mould board of the plough has the upper end thereof given a considerable forward turn as best shown in Figure 5 and the general arrangement of the plough is such that the earth dug thereby will be deflected and discharged into the adjacent wheel and be caught by the buckets and elevated by such wheel. The wings 28 are so placed in respect to the wings of the buckets that any dirt which might slide off the wings of the rising buckets will be caught by the wings 28 and deflected to a lower bucket instead of being permitted to accumulate around the hub of the wheel.

The machine as above described can be used for excavating purposes where it is desirable that the excavated dirt be caught in the box and deposited in a selected location. Under other circumstances, however, it might not be necessary to collect the excavated dirt and

under such condition, the collecting box could be dispensed with and the earth discharged from the wheel directly onto the ground at which time it will be deposited to the side of the ditch made by the plough. Under conditions where the earth is a free flowing earth, the positive worm delivery could be dispensed with and an inclined collecting and discharging chute 67 such as shown in Figure 6 can be used. In this latter figure, I have also shown the box as dispensed with.

What I claim as my invention is:—

1. In an earth excavating machine, a rotatably mounted wheel embodying a relatively wide rim having side flanges, a hub, spokes extending between one of the flanges and the hub at one side of the wheel, the other side thereof being open, spaced cross members located on the inner side of the rim and forming with the rim a plurality of earth elevating buckets and earth deflecting means adjoining the hub and extending transversely of the wheel.
2. In an earth excavating machine, a rotatably mounted wheel embodying a relatively wide rim having side flanges, a hub, spokes extending between one of the flanges and the hub at one side of the wheel, the other side thereof being open, spaced cross members located on the inner side of the rim and forming with the rim a plurality of earth elevating buckets and earth deflecting plates spaced from and concentric to the hub and passing across the wheel.
3. In an earth excavating machine, a rotatably mounted wheel embodying a relatively wide rim having inwardly extending side flanges, a hub, spokes extending between one of the flanges and the hub at one side of the wheel, the other side of the wheel being open, said spokes carrying transversely extending flanges adjacent the rim and adjacent the hub, such flanges adjacent the rim being provided with deflecting wings at their inner edges and such flanges adjacent the hub being provided at their outer edges with deflecting wings positioned concentric to the hub, the cross flanges adjacent the rim forming with the rim flanges a plurality of elevating buckets.

Signed at Assiniboia, Saskatchewan, this
17th day of April, 1928.

ADAM CLARK.
